J. R. MILLAR

PADDING MATERIAL

Filed Dec. 26, 1923

INVENTOR
JOHN R. MILLAR

BY
ATTORNEY

Harry J. Schneider

UNITED STATES PATENT OFFICE.

JOHN R. MILLAR, OF OAKLAND, CALIFORNIA ASSIGNOR TO CALIFORNIA COTTON MILLS COMPANY, OF OAKLAND, CALIFORNIA, A CORPORATION OF CALIFORNIA.

PADDING MATERIAL.

Application filed December 28, 1923. Serial No. 682,839.

My invention is an improved upholstery padding particularly applicable to automobile seat backs.

The method of manufacturing seat padding heretofore employed consisted of forming comparatively flat pads which were forced into the upholstery pockets.

In use the padding was forced into the sides of the pockets, and a major portion of the effectiveness was thus lost.

The object of my invention is to form a padding substantially circular in cross section, and with a suitable longitudinal reinforcement, which when positioned in the upholstery pocket will require a much greater length of time to flatten out. Also a greater amount of resiliency in the direction of the pressure will ensue from this type of padding.

Another object is to provide a padding with an outer coating or sleeve of a material of high tensile strength, and a filling of inexpensive material but of low tensile strength, i. e. an outer coat of long staple cotton, and an inner filling of short lengths of jute, waste cotton, and other short fibre material.

Other objects and advantages will be more specifically described in the following detailed description.

In the annexed drawing in which my invention is illustrated:

Figure 1 is a perspective view with parts broken away to show the construction of my padding.

Figure 2 is a sectional view taken on the line 2—2 of Figure 1.

Figure 3 is a transverse sectional view of a modified form of padding.

Figure 4 is a transverse sectional view of another modification of the padding.

Referring more particularly to the drawing, my padding consists of an outer layer or cover 1, which is preferably formed of a

long fibre material, and which is wrapped about or filled with a filling 2. This filling may be an inexpensive short fiber material.

To increase the tensile strength of the padding, I provide a reinforcing strip 3, which is placed between the overlapping edges of the layer or cover 1, and is preferably secured to both edges, such as by an adhesive placed upon both faces of the strip.

In the form shown in Figure 3 the reinforcing strip 4 extends through the filling material 2, and may or may not be secured thereto as desired. I find it advisable to place an adhesive on at least one face of the strip 4 thus binding the strip securely to the filling 2.

If the material 2 is placed in the cover 1 after the cover has been formed into a cylinder, the overlapping edges of the cover may be secured together by any suitable means.

If desired the edges of the cover 1 may butt and the reinforcing strip 6 extend over the seam between the abutting edges and is secured to the cover, preferably by an adhesive.

Having described my invention, I claim:

1. An upholstery pad comprising a cylindrical fabric cover having overlapping longitudinal edges, a reinforcing strip secured to said edges, and a filling core in said cover.

2. An upholstery pad comprising a filling core, a cover surrounding said core, said cover having overlapped longitudinal edges, a reinforcing strip positioned between said edges, and means for securing said strip to said edges.

3. A padding material comprising an outer cover, the edges of said cover overlapping, a reinforcing strip extending between the overlapping edges and secured thereto, and a filling core in said cover.

In testimony whereof I affix my signature.

JOHN R. MILLAR.
